UNITED STATES PATENT OFFICE.

WALTER F. AYARS, OF BRIDGETON, NEW JERSEY.

STREET-CLEANING MACHINE.

1,274,664.

Specification of Letters Patent.

Patented Aug. 6, 1918.

Application filed January 30, 1918. Serial No. 214,503.

To all whom it may concern:

Be it known that I, WALTER F. AYARS, a citizen of the United States of America, residing at Bridgeton, in the county of Cumberland and State of New Jersey, have invented new and useful Improvements in Street-Cleaning Machines, of which the following is a specification.

This invention comprehends in general 10 improvements in that class of inventions known for brushing and scrubbing and more particularly has reference to a street cleaning machine.

As the primary aim and object, this invention 15 contemplates the provision of a machine of the above mentioned character wherein improved coöperative sweeping, elevating and conveying means are arranged to operate simultaneously with respect to each 20 other so as to assure the removal of dirt from the street and the depositing of the dirt within a receiving compartment in the body of the machine.

It is an additional object of this invention 25 to provide a machine of the above mentioned character wherein the elevating means is designed to operate through the dirt receiving trough at the forward end of the body of the machine so as to remove the dirt from 30 the trough and elevate it and consequently deposit it on a conveying means which in turn conveys the dirt to the dirt receiving compartment.

As a further improvement this invention 35 includes the provision of improved coöperative guiding and tripping means designed for use in conjunction with swinging buckets of the elevating means so as to assure of the proper actuation of the buckets during the 40 operation of the machine.

It is a more specific object of this invention to provide improved sprinkling means for sprinkling or spraying the dirt in the dirt compartment in the body for preventing 45 dust, etc.

Among the other aims and objects of this invention may be recited the provision of a device of the character described with a view to compactness, and in which the number of 50 parts are few, the construction simple and the cost of production low and the efficiency high.

Other objects as well as the nature, characteristic features and scope of this invention 55 will be more readily apparent from the following description taken in connection

with the accompanying drawings and pointed out in the claims forming a part of this specification.

The invention is clearly illustrated in the 60 accompanying drawings, wherein:

Figure 1 is a longitudinal sectional view of the invention.

Fig. 2 is a top plan view of the machine with the top of the body removed. 65

Fig. 3 is a transverse section taken on the line 3—3 of Fig. 1 in the direction in which the arrows point.

Fig. 4 is a transverse section taken on the line 4—4 of Fig. 1 in the direction in which 70 the arrows point.

Similar characters of reference are employed in all of the above described views to indicate corresponding parts.

Referring now, more particularly, to the 75 accompanying drawings, there is provided a motor vehicle consisting generally of a frame 1 the rear portion of which is designed for a body or casing 2 of a rectangular configuration. A rear axle 3 is journaled 80 through the rear portion of the frame or body and has supporting wheels 4 operably mounted on the respective ends thereof while other supporting wheels 5 are also mounted on the respective ends of the front axle 6. 85 A hood 7 is mounted on the forward end of the frame and is adapted to cover suitable motive power while the transmission box or casing 8 is mounted beneath the body near the forward end thereof. A rotatable shaft 90

9 extends from the transmission box 8 and carries on its outer end a sprocket wheel 10 over which operates a chain 11 which in turn is trained about another sprocket wheel 12 at the end of the rear axle 3. A driver's seat 95 13 is mounted forwardly on the body in spaced relation to the dash while the steering wheel 14 is operably connected to the front axle 6 and is within convenient reach of the driver when in position on the seat so 100 as to assure the proper actuation of the vehicle. It is to be understood that the parts enumerated may be of any convenient construction and this invention is not limited to the particular construction shown as it is 105 apparent that other means may be employed for transmitting motion to the rear axle and likewise it is unnecessary to employ motion transmitting means to the rear axle.

The bottom of the body 2 is formed near 110 its front end with an opening while journaled through the sides of the body above

the opening is a transverse shaft 16 on which is carried a rotary sweeping brush 17 consisting of a cylindrical body 19 from which projects bristles 18. This brush of course, is positioned through the opening 15 while the bristles are designed to be engaged upon the ground for sweeping dirt, etc. A dirt receiving trough 20 is formed in the bottom of the body near the front end thereof while an inclined apron 22 depends from the trough and is positioned in the opening 15 and in closely spaced relation to the ground and in proximity to the brush bristles 19 so that the dirt which is swept from the surface 15 of the street will be directed up the apron and will be deposited in the trough 20.

In order to actuate the sweeping brush simultaneously with the actuation of the motor vehicle a stub shaft 23 is journaled through one side of the body or casing and has a sprocket wheel 24 mounted on the outer end thereof and over this sprocket wheel a chain 25 is trained. This chain is also trained about another sprocket wheel 26 on the opposite end of the rear axle 3 so that during the rotation of the rear axle 3 of the stub shaft will be rotated in a corresponding direction. A gear 27 is also carried by the shaft 23 and is positioned adjacent the outer face of the side wall of the body and meshes with another gear 28 on the projecting end of the shaft 16 and is designed to be rotated in the opposite direction from the gear 27 and the shaft 23 so as to consequently assure of the brush 17 sweeping the dirt upon the apron 22.

With a view toward providing the improved elevating means for removing the dirt from the trough 20, a plurality of shafts 29 are arranged at right angles to the front wall and longitudinally of the body having their respective ends journaled in the front wall and in brackets 30 and 31 which extend respectively from the opposite points on the side walls and from the upper end of the apron 22 the shafts being positioned in proximity to the opposed upper and lower corners of the body as indicated in Fig. 3. Sprocket wheels 32 are carried on each of the shafts 29 while operating about these wheels are spaced endless chains 33 between opposed links of which and at uniformly spaced intervals throughout their lengths are swingingly connected transverse buckets 34 which may be and preferably are substantially V-shaped in cross section. It is to be observed that the upper and lower and side lays of the chains 33 are respectively arranged in close relation to the upper and lower and side walls of the body. A wear plate 35 is mounted in the bottom of the trough 20 while an arcuate boot 36 is mounted in one end of the trough and extends upwardly in close relation to one side wall 65 and is designed to coöperate with the

buckets 34 as they pass through the trough. The buckets are connected so that they will normally lie in an upright position. In order to trip the buckets immediately before they enter the trough a tripping pin 37 extends outwardly from the inner surface of the front wall in proximity to the wear plate 35 and lies in the path of movement of the buckets and is designed to successively swing the buckets into a substantially inverted position so that one of the side edges of each of the buckets will be engaged on the wear plate while the relation of the lower leg of the chain is close to the wear plate so as to prevent the buckets from righting themselves until they have passed by the boot 36. In tripping the buckets of the upper lay of the chain a guiding shoe 38 extends from the front wall and lies in the path of movement of each of the buckets so as to swing the buckets about their pivots when engaged thereby. In this connection it is to be noted, the shoe is arcuate while extending from the front wall is another tripping pin 39, which is designed to engage the upper edge of each of the buckets immediately after they pass over the shoe and assure of a complete dumping of the buckets for a purpose which will presently become apparent.

In actuating the elevating means simultaneously with the sweeping means a bevel gear 40 is mounted on one projecting end of one of the shafts 29 and meshes with another bevel gear 41 carried by the stub shaft 42 journaled transversely in one side wall of the body. A sprocket wheel 43 is carried by the outer projecting end of the stub shaft 42 while a chain 44 operates about the sprocket wheel 43 and also about another sprocket wheel 45 carried by the projecting end of the shaft 16. This motion transmitting means, of course, assures of the actuation of the elevating means.

Coöoperating with the elevating means is the improved conveying means and this conveying means consists of a lower shaft 46 journaled in brackets 47 which project from the front wall and terminate so as to position the shaft beneath the upper lay of the chains of the elevating means. Another shaft 48 is journaled transversely in the sides of the body near the top thereof while one end projects beyond one side of the body. Spaced sprocket wheels 49 are mounted rigidly on the shafts 46 and 48 while operating about the alining sprocket wheels on the shafts are endless chains 50. These chains carry an endless belt 51 which has mounted transversely thereacross at uniformly spaced intervals a plurality of stationary buckets 52. The conveyer, of course, is inclined upwardly while the upper lay moves in the direction toward the rear end of the body so that the dirt which is 130

deposited from the swinging buckets 34 falls upon the endless belt 51 and in the buckets 52 and, of course, is conveyed upwardly and subsequently deposited in the dirt receiving compartment 53 formed in the rear end of the body by the partition 54. An inclined protecting partition 55 is mounted between the side walls of the body and serves to return any dirt which fails to 10 leave the conveyor.

Suitable means for actuating the conveying means simultaneously with the sweeping means and the elevating means and in the same direction as the sweeping means 15 consists of the sprocket wheel 56 carried by the projecting end of the shaft 48 and over which sprocket wheel operates a chain 57 which also operates about another sprocket wheel 58 on the shaft 16. 20 As intimated there is provided means for sprinkling the dirt in the compartment 53 and in reducing this feature of the invention to practice a tank 59 is mounted transversely on the dirt compartment and is designed for receiving suitable liquid such as 25 water which is dispensed therefrom through the medium of a nozzle 60 depending from the tank. A door 61 is swingingly mounted in the back of the body and establishes 30 access to the compartment 53 when it is desired to remove the dirt therefrom.

The mode of operation of the present invention may be reviewed as follows:

Assuming that the parts have been assembled in the manner described and as indicated in the drawings. Upon the forward movement of the vehicle rotary motion will be transmitted from the rear axle 3 to the sweeping brush 17 so as to rotate the latter in the opposite direction and consequently assure of dirt, etc., being swept up the inclined apron 22 and deposited in the dirt trough 20. During this movement, the elevating means which is operably connected to the shaft 16 of the sweeping brush through the instrumentality of the sprocket wheels 45 and 43 and the chain 44 as well as the stub shaft 42 and the inter-meshing gears 40 and 41, will be actuated so that the buckets 34 will be passed through the trough 20 so as to engage the dirt in the bottom thereof and elevate the dirt upwardly. These buckets are first tripped to assume the position as indicated in Fig. 3 by the tripping pin 37 so as to assure of a scraping of dirt from the trough and are subsequently tilted and tripped by the guiding shoe 38 and the tripping pin 39 so that the contents thereof will be deposited upon the inclined 60 and endless conveyor and apron 51. As is apparent this apron operates simultane-

ously with the brush 17 and in the same direction so that the dirt will be conveyed upwardly and deposited in the dirt compartment 53. Suitable means, of course, not shown may be employed for actuating the sprinkling means so as to reduce the formation of dust when the machine is in operation.

It is believed in view of the foregoing description that a further detail description of the invention is entirely unnecessary.

Likewise it will be believed that the advantages of the invention will be readily apparent.

As many changes could be made in the above construction and many apparently widely different embodiments of this invention could be made without departing from the scope thereof it is intended that all matter contained in the above description or shown in the accompanying drawings shall be interpreted as illustrative and not in a limited sense. It is also to be understood that the language used in the following 85 claims is intended to cover all the generic and specific features of the invention herein described and all statements of the scope of the invention which as a matter of language 90 might be said to fall therebetween.

The invention having been described, what is claimed as new and useful is:

A street cleaning machine including a vehicle body, a dirt trough formed in the bottom thereof formed near the forward end, a boot mounted near one end of the trough, a dirt compartment near the rear part of the body, brushing and sweeping means for depositing dirt in the trough, elevating means operably mounted in the body and passing through the trough and embodying a plurality of shafts arranged near the upper and lower corners of the body, spaced sprocket wheels carried by the shafts, endless chains operating about the alining sprocket wheels, a series of buckets V-shaped in cross section having their ends swingingly connected to opposed links of the chains and normally positioned upright and between the chains, a trip member mounted in the body and designed to tilt each of the buckets as they successively enter the trough so as to facilitate filling of the buckets, a guide mounted near the top of the body for dumping the buckets, another trip member coöoperating with the guide for assuring of the successive dumping of the buckets, and conveying means operably mounted in the body for receiving dirt from the buckets and depositing it in the dirt compartment.

In testimony whereof I affix my signature.

WALTER F. AYARS.
